UNITED STATES PATENT OFFICE.

LAURA E. MAILLEUE, OF VANCOUVER, BRITISH COLUMBIA, CANADA.

SURGICAL BUST SUBSTITUTE.

1,417,930.

Specification of Letters Patent. Patented May 30, 1922.

Application filed May 14, 1919. Serial No. 297,030.

To all whom it may concern:

Be it known that I, LAURA E. MAILLEUE, a subject of Great Britain, and resident of Vancouver, Province of British Columbia, 5 Canada, have invented certain new and useful Improvements in Surgical Bust Substitutes, of which I hereby declare the following to be a full, clear, and exact description, such as will enable others skilled in the 10 art to which it appertains to make and use the same.

The objects of the invention are to provide a convenient and comfortable substitute for the bust of a woman, which has been removed by a surgical operation, and which 15 will relieve the flattened appearance caused by the operation and will reproduce the exact shape of the amputated part.

The invention includes means for attaching 20 the device to either the right or left side of the subject, and for making it adjustable to fit the form closely so that the natural appearance of the figure will be restored and the attaching means will not interfere with 25 the fit of the clothing worn over it.

The invention comprises the bust substitute or padded member, and the manner of constructing the same and of attaching it to the figure hereinafter described, shown in 30 the accompanying drawings and specifically pointed out in the claims.

In the accompanying drawings, Fig. 1 is a perspective of the device, showing the method of attaching the same, Fig. 2, is a 35 transverse section of the substitute bust, showing the manner of constructing the same and Fig. 3 is a perspective view of the device removed from the subject.

In these views, A is the bust substitute 40 generally which comprises a base in the form of an annular casing A', preferably formed of soft chamois skin, having a filler B. This annular casing A' is extended upon a ring C formed of whale bone or other somewhat 45 resilient material which will retain the shape of the casing.

Arched above the casing are shown, resilient strips D, crossing each other, which are covered on the outer and inner sides with 50 layers D' of suitable light and dainty material such as dimity, or silk, and, if desired, a layer of cotton or other cushioning material (not shown) may be interposed between the outer and inner layers D', D'.

55 Inasmuch as this last feature constitutes

no essential part of my invention, is so obvious, and its presence in the drawing would tend to confuse, it is deemed advisable to omit it from the illustration.

The edge may be finished with a border 60 of lace if desired, thus giving an attractive appearance to the device. In order to secure the substitute bust in place so that it can not move about after it has been attached, a shoulder strap E is attached at one end to 65 the upper edge of the casing, preferably a little to one side of the center and the other end of the shoulder strap is attached to a belt F which passes around the body and back underneath the arm pits. 70

This belt is permanently attached to the substitute bust at G, at one end, and is provided with attaching means at H, H, at the other end. To permit the belt and shoulder strap to accommodate themselves closely to 75 the contours of the body, the central portion of the shoulder strap, where it passes over the shoulder, is formed of elastic fabric at I, I. Two narrow bands being employed to permit them to fit closely the curves of the 80 shoulder, and the portions of the belt where it passes under the arms are preferably formed of three narrow elastic bands at the attached side, and two or more at the detachable side, thus permitting the bands to 85 automatically accommodate themselves to the curves of the side.

A central portion of the belt is formed of a wide fabric band, the ends of which curve downwardly, thus making it fit perfectly the 90 back and shoulder blades. In this manner, a perfect restoration of the original figure is obtained and the elastic holding bands are flattened over the sides and back and shoulder so that they can not be noticed underneath the clothing. 95

Having described the invention what I claim as new and desire to secure by Letters Patent is:—

1. A surgical bust substitute comprising 100 an annular casing of soft pliable material, a filler disposed within said casing, a frame composed of resilient strips arched above and secured to said casing, a fabric cover for said frame, and means for attaching the 105 structure to a form.

2. A surgical bust substitute comprising 110 an annular casing of soft pliable material, a filler disposed within said casing, a ring of resilient material disposed within said

casing for retaining the same in shape, a frame composed of resilient strips arched above and secured to the casing, a fabric cover for said frame, and means for attaching the structure to a form.

3. A surgical bust substitute comprising an annular casing of soft pliable material, a filler and a ring of resilient material disposed within said casing for retaining the same in shape, a frame of resilient strips

arched above and secured to the casing, a fabric cover enclosing the frame, and means for attaching the structure to a form.

In testimony whereof, I hereunto set my hand this 17 day of April, 1919.

LAURA E. MAILLEUE.

In presence of—

Wm. M. MONROE,
S. W. SANGSTER.
